UNITED STATES PATENT OFFICE

WILLIAM G. SHELTON, OF ST. LOUIS, MISSOURI

HAIR-WAVING DEVICE

Application filed January 21, 1929. Serial No. 333,895.

My invention relates to the art of permanent curling or waving of the human hair and consists in a novel apparatus for applying heat to the curled strand of hair and 5 the supply wrapped about the same.

One of the objects of my invention is to provide means for applying the heater to the strand of hair at as close a point to the scalp of the user as possible. It is necessary, 10 in the use of heaters of this type, to protect the scalp of the user from burns or scalding due to the heater or steam or hot fluid escaping from the supply or curl which have moisture applied thereto during the curling operation and it is a further object of 15 my invention to provide an effective seal for this purpose.

It is customary to apply a clamp to the strand of hair adjacent to the scalp and to 20 mount the heater on this clamp. The clamp has heretofore included strips or slabs of cork, rubber or similar yielding insulating material, the effectiveness of which was limited because the clamping of a strand of hair 25 between the opposed edges of the slabs would result in indentations being formed in these edges which indentations, in later applications of the clamp, would form passageways for the seepage of steam and hot 30 fluid to the scalp of the user. In such clamps as I am familiar with, the yielding clamp elements have been of such thickness that the curling rod and heater could not only be positioned as close to the scalp as desired 35 but also the clamp and heater could not be held in as stable a position as desired.

Another object of my invention is to remedy this unsatisfactory condition.

It is a further object of my invention to 40 provide hair-engaging strips for the clamp which shall be easily renewable and will form an effective seal between the scalp of the user and the heater.

These and other detailed objects of my 45 invention are attained by the use of the structure illustrated in the accompanying drawings in which—

Figure 1 is a perspective view of the heater member.

50 Figure 2 is a transverse vertical section

through the same showing it applied to a strand of hair.

Figure 3 is a perspective of the clamp on which the heater is mounted.

Figure 4 is a perspective of the outer portion or envelope of the renewable strip for the clamp.

Figures 5 and 6 are perspectives of fillers for the envelope shown in Figure 4.

Figure 7 illustrates the manner of assembling the strips with the envelope. 60

The heater member has an arcuate body 1 containing an electric resistance heating element and mounting a block 2 of insulating material on its convex surface. Spring clips 3 are attached to each side of the block 2 and each clip comprises an end portion secured to the block by a rivet 4, or other suitable means, and an offset intermediate portion and an outer portion 5 spaced from block 2. 70

Separately formed arms 6 are mounted upon the outer portions 5 of the spring clips and project upwardly and downwardly therefrom. The upwardly projecting portions form handles 7 for manipulating the heater and the downwardly projecting portions 8 terminate in jaws 9 extending under the lower edges of the heater 1 and adapted to project to grip the strand of hair S and the supply P. It will be understood that the spring clips 3 hold or tend to hold the jaws in the full line position shown in Figure 2 but the compression of the handles 7 towards each other will move the jaws 9 away from each other so as to permit application or removal of the heater member to and from the cylinder-like body formed by the strand of hair wrapped about the rod 10 and enclosed in the supply P. 75 80

By mounting the arms 6 as shown, the structure is simplified as compared with devices including hinges and spring devices for closing the jaws on their hinges, and this arrangement also forms a pivotal mounting for the arms 6 spaced substantially from the center of the heater and farther apart than the faces of the jaws so that movement of the jaws into and out of their gripping position is accompanied by a minimum of vertical movement thereby permitting the device to 90

be applied to the strand of hair nearer to the scalp than in devices where the arms are pivoted on the center line of the heater.

The heater and curling rod are mounted upon the clamp device comprising a pair of bars 11 pivoted together at one end as indicated at 12 and provided with a releasable latch 13 at their other end. The pivoted end of the bars is provided with an upstanding lug 14 having a slot 15 adapted to receive a squared pin 16 extending from one end of the curling rod 10. The latch 13 is provided with an upstanding lug 17 adapted to engage a similar pin formed on the other end of the curling rod.

Each of the bars 11 is preferably formed of channel section as best shown in Figure 2 and these bars are open at their ends.

A sealing and insulating member 18 is provided for each clamp bar and consists of a loop of tubular material applied to the lower flange of the bar and this loop is preferably formed of tubular elastic material and is closed. A tube formed of rubber of substantial thickness may be used for this purpose and may be stretched lengthwise to fit over the bar flange, the tube being wide enough to project from the edge of the flange a substantial distance so that, when the bars are clamped together, the upper leg of the loop will be compressed along the strand of hair to form a tight joint. The lower leg of the loop has some play relative to the bar and provides a more comfortable support for the clamp and heater and also contributes to the insulation of the heater from the scalp A.

In the preferred embodiment of my invention, the tubular loop 18 is provided with inserts 19 and 20 of flat and comparatively rigid material, such as bakelite or vulcanized rubber. By slitting one end of the loop 18, as indicated at 21, the fillers 19 and 20 may be inserted in the upper and lower legs of the loop. By twisting the loop inside out, so to speak, the slit 21 may be turned inwardly so that it is not visible, thereby adding to the appearance of the product. Figure 7 illustrates the tube as it is being turned from the position with the slit 21 outwardly to a position with the slit inwardly.

The loop 18 may be formed of a tube with ends abutting each other and this will simplify the manufacture and eliminate the slit.

I show the lower filler 20 as being provided with a lateral offset 22 and this feature will provide a wider base for the clamp, thereby increasing its stability and reducing the tendency of the apparatus to turn from its vertical position and making it more comfortable for the user. This feature will also provide finger holds spaced from the metal of bars 11 whereby the operator may pick up the clamp when the bars are hot.

The described structure provides a joint 65 which is tight against water and steam

throughout successive applications of the clamp. When the elasticity of the rubber is exhausted by repeated heatings, the loops 18 may be discarded and new ones applied to the bars without replacing the clamps and, 70 obviously, the replacing of the loops will be accompanied by substantially less expense than the replacement of the entire clamp member. The quadruple layer of rubber between the scalp of the user and the heater member and the relatively small proportion of metal provided by the bars 11 adequately insulate the scalp of the user from the heat generated in the heater.

The described structure is adapted for variations in the type of equipment with which it is used as the rubber loops may be stretched over different lengths of bars and may have fillers of different widths and thicknesses inserted therein. For example, the upper fillers 85 19 may be of increased thickness to provide a greater area of contact with the strand of hair.

It is obvious that the details of the structure may be varied substantially without departing from the spirit of my invention and I contemplate the exclusive use of such modifications in the device as come within the scope of my claims.

I claim:

1. In a device of the class described, a clamp comprising a pair of rigid bars pivoted to each other near one end and an individual endless tube of compressible material detachably applied around each of said bars so as to contact with a strand of hair between said bars and to space said bars from the scalp of the user, and means within said tube giving it a flattened shape for presenting a flat surface thereof to the scalp of the user while pressure is applied to said tube through said bars in the direction of the width of the flattened portion.

2. A clamp for hair waving apparatus comprising a pair of channel-shaped bars pivoted to each other near one end, an individual loop of tubular elastic material extending lengthwise around the lower flange of each bar and across the end thereof, and a flat filler of rigid material inserted in one 115 of the legs of said loop.

3. A clamp for hair waving apparatus comprising a pair of channel-shaped bars pivoted to each other near one end, an individual loop of tubular elastic material extending lengthwise around the lower flange of each bar and across the end thereof, and a flat filler of rigid material inserted in the lower leg of said loop, said filler having a lateral extension of restricted length for increasing the stability of the apparatus when applied to the head of the user.

4. As a new article of manufacture for use in hair waving clamps, a closed loop of tubular elastic material provided with a slit 130

- at one end for admitting a flat filler to the interior of the tube.
5. As a new article of manufacture for use in hair waving clips, a closed loop of tubular material provided with a slit at one end for admitting a flat filler to the interior of the tube.
6. As a new article of manufacture for use in hair waving clamps, a closed loop of tubular elastic material provided with a slit at one end for admitting a flat filler to the interior of the tube, and a flat rigid filler inserted in one of the legs of said loop.
7. A clamp for hair waving apparatus comprising a pair of channel-shaped bars pivoted to each other near one end, and an individual loop of elastic material extending lengthwise around the lower flange of each bar and across the ends thereof, and a rigid filler in said loop for giving the same a flat shape in cross section.
8. A clamp for hair waving apparatus comprising a pair of channel-shaped bars pivoted to each other near one end, an individual loop of tubular elastic material extending lengthwise around the lower flange of each bar and across the end thereof, and a flat filler of rigid material inserted in the legs of said loop.
9. A clamp for hair waving apparatus comprising a pair of channel-shaped bars pivoted to each other near one end, an individual loop of tubular elastic material extending lengthwise around the lower flange of each bar and across the end thereof, and flat fillers of rigid material inserted in the legs of said loop, the upper leg of said loop being seated against the back of the bar and the lower leg of said loop being free to move yieldingly relative to the bar.
10. As a new article of manufacture for use in hair waving clamps, a loop of tubular elastic material, and separate flat rigid fillers inserted in the legs of said loop.
11. As a new article of manufacture, for use in hair waving clamps, a loop of tubular elastic material, and a flat rigid filler inserted in one of the legs of said loop and having a lateral projection providing greater width at one part of said loop than at another.
12. As a new article of manufacture for use in hair waving clamps, a loop of tubular material adapted to be twisted so that its inner face is on the outside and vice-versa, and provided with a slit at one end for admitting one or more flat rigid fillers to the interior of the tube, whereby the fillers may be inserted from the exterior of the tube and the tube twisted to position said slit on its inner face.
13. A clamp for hair waving apparatus comprising a pair of bars pivoted together at one end, and a plurality of strips of yielding material detachably applied to each of
- 70
- 75
- 80
- 85
- 90
- 95
- 100
- 105
- 110
- 115
- 120
- 125
- 130
- said bars one above the other, and means between said strips for maintaining the same in flattened shape while pressure is applied through said bars to the edges of said strips.
14. A clamp for hair waving apparatus comprising a pair of bars pivoted together at one end and a cushion therefor consisting of a plurality of strips of elastic material, said cushion being detachably secured to the bar solely by its own elasticity.
15. As a new article of manufacture for use in hair waving clamps, a loop of tubular elastic material, and a flat filler of rigid material inserted in one of the legs of said loop.
- In testimony whereof I hereunto affix my signature this 17th day of January, 1929.
- WILLIAM G. SHELTON.
